UNITED STATES PATENT OFFICE.

RUSSEL G. WOODWARD, OF WAUKEGAN, ILLINOIS, ASSIGNOR TO UNION SPECIAL MACHINE COMPANY, OF CHICAGO, ILLINOIS, A CORPORATION OF ILLINOIS.

EDGE-GUIDE AND STITCH-FINGER FOR SEWING-MACHINES.

1,071,598.

Specification of Letters Patent. Patented Aug. 26, 1913.

Application filed December 6, 1906. Serial No. 346,573.

To all whom it may concern:

Be it known that I, RUSSEL G. WOODWARD, a citizen of the United States, residing at Waukegan, in the county of Lake, 5 State of Illinois, have invented certain new and useful Improvements in Edge-Guides and Stitch-Fingers for Sewing-Machines, of which the following is a description, reference being had to the accompanying drawings and to the letters and figures of reference marked thereon.

My invention relates to improvements in sewing machines, and has for its objects to provide an edge guide and stitch finger, 15 which are simultaneously adjustable in a direction at an angle to the line of feed.

My invention consists in the novel parts and improvements hereinafter shown and described.

20 In the accompanying drawing:—Figure 1 shows in plan, a throat plate provided with my edge guide and stitch finger, and also the relation of the same to the elements of an overedge stitching machine. Fig. 2 is a 25 side elevation of my improved edge guide and stitch finger. Fig. 3 is a sectional view taken on the line 3, 3 of the throat plate shown in Fig. 1. Fig. 4 shows in perspective, a throat plate with my improvements 30 attached thereto.

In the drawings, the throat plate 1 is provided with slots 2, 3, and 4, through which operates the feed dog to move the fabric. The direction of feed is longitudinal of the 35 throat plate as viewed in Fig. 1. The throat plate is provided with a recess 5, in which is adjustably mounted a plate 6 carrying an edge guide 7. This plate is secured in its adjusted positions, by screws 8, 40 8. As shown in the drawings, the edge guide is formed integral with the adjustable plate. It will, however, be observed that said guide may be attached to the plate in any other manner.

45 In the present embodiment of my invention, the stitch finger 9 is formed by tapering the rearward portion of the edge guide, that portion extending toward the needle, so that in reality, the edge guide and stitch finger form one continuous member. In order to support the rearward end of the edge guide and stitch finger more firmly, I have provided a laterally extending lug 10, 50 which is seated in a recess 11 in the throat plate. Extending rearwardly from the lug 55

10, to a point adjacent the rearward end of the stitch finger is a ledge 12, which serves to support the outer edge of the fabric at the point of stitching. The needle 14 passes through the material and enters the opening formed between the ledge 12 and the wall 13 of the throat plate. Cooperating with said needle, are the elements of an overedge stitch mechanism, which as illustrated in the drawings, consists of a loop spreader 14, and a thread carrying looper 15. The loop spreader takes the loop from the needle beneath the fabric, carrying the same into the path of movement of the thread carrying looper, which passes 70 through said needle loop and carries its own loop into the path of the descending needle, thus forming stitches around the edge of the fabric, and over the stitch finger 9. The feed of the fabric carries the stitches in the 75 usual manner off the stitch finger. The stitch finger as shown in the drawing, therefore, extends across the plane of the fabric and serves also as an edge guide. When it is desired to adjust the width of the overedge 80 stitch, the screws 8, 8 are loosened and the plate 6 is moved in or out, thus increasing or decreasing the distance between the edge guide and the needle which gives a corresponding increase or decrease in the width 85 of the overedge stitch. It will thus be seen that by making the guide and tongue of the throat plate integral that I am able to properly control the edge of the goods from the front of the guide to the stitching point 90 or where the threads are lapped over the edge of the goods. Inasmuch as the edge guide extends well to the front of the stitching point, the loose ends of threads will be turned up and the cut edge properly directed to the stitching mechanism so that said edge will be covered by the overedge stitches. 95 Having thus described my invention, what I claim as new and desire to secure by Letters Patent is:—

1. The combination of a needle, a work support having feed slots therein, and a combined edge guide and stitch finger rigidly carried thereby, said edge guide and stitch finger having an edge guiding portion 105 extending rearwardly to a point beyond the needle, whereby the edge of the material is guided until after the same is covered with the stitches, said edge guide having a work supporting ledge projecting laterally there- 110

from toward the needle, the upper face of the ledge lying substantially in the plane of the work support, whereby the edge of the material is supported and guided as it passes the needle.

2. The combination of a needle, a work support having feed slots therein, and a combined edge guide and stitch finger rigidly carried thereby, said edge guide and 10 stitch finger having an edge guiding portion extending rearwardly to a point beyond the needle, whereby the edge of the material is guided until after the same is covered with the stitches, said edge guide having a work 15 supporting ledge projecting laterally therefrom toward the needle, the upper face of the ledge lying substantially in the plane of the work support, whereby the edge of the material is supported and guided as it passes the 20 needle, and means for adjusting said edge guide and stitch finger relative to the needle.

3. In an overedge stitching machine, the combination of a throat plate, an edge guide, a stitch finger carried thereby, an

adjustable plate supporting said edge guide, 2 and a supporting lug, extending from the rearward end of said edge guide and engaging the throat plate.

4. An overedge stitching machine including in combination, a throat plate, a stitch 30 finger having a rearwardly projecting part over which the stitches are laid, the said rearwardly projecting part being spaced from the throat plate and extending across the plane thereof, whereby an edge guide 35 for the material is formed.

5. In an overedge stitching machine, the combination of a throat plate, an edge 40 guide, an adjustable plate supporting said edge guide, and a supporting lug, extending from the rearward end of said edge guide and engaging the throat plate.

In testimony whereof I affix my signature, in presence of two witnesses.

RUSSEL G. WOODWARD.
